MULTIPLE HYDRAULIC MOTOR OPERATION

Hans Ernst, Cincinnati, Ohio, assignor to The Cincinnati Milling Machine Company, Cincinnati, Ohio, a corporation of Ohio

Application June 2, 1932, Serial No. 614,980

15 Claims. (Cl. 60—97)

This invention relates to hydraulic circuits and more particularly to means for connecting a plurality of hydraulic motors to a common pressure source for parallel operation at positively maintained equal or proportionate rates.

It is well known that a plurality of hydraulic motors connected in parallel directly to a common source of pressure cannot be operated at equal

10 rates because the respective work resistances ordinarily do not remain the same. What happens is that the motor having the lower work resistance does not present enough resistance to build the pressure up to the point where it will overcome the work resistance of the other parallel motor.

15 The result is that one motor decelerates and the other accelerates thus disturbing the relative rates of operation of the motors.

It is therefore one of the principal objects of this invention to provide mechanism for connecting a plurality of motors in parallel to a common pressure source in such a manner that each may be operated at the same rate or at proportionately different rates without reverse retarding effects of one upon the other.

20 A further object of this invention is to provide in combination with a mechanism for subdividing a main flow to a plurality of motors, automatic compensating means functionally sensitive to flow variation in the respective branch lines for maintaining the subdivisions constant irrespective of variation in work resistances.

25 An additional object of this invention is to provide an hydraulic circuit for the parallel operation of a plurality of hydraulic motors containing adjustable means whereby the relative rates of movement of the motors may be varied with respect to each other.

30 Other objects and advantages of the present invention should be readily apparent by reference to the following specification considered in conjunction with the accompanying drawing illustrative of one embodiment thereof, but it will be understood that any modifications may be made in the specific structural details thereof within the scope of the appended claims without departing from or exceeding the spirit of the invention.

35 Referring to the drawing in which like reference characters indicate like or similar parts:

Figure 1 is a semi-diagrammatical view showing one method of coupling a plurality of motors in parallel to a common pressure source for simultaneous operation.

40 Figure 2 is a semi-diagrammatic view showing

the coupling of reciprocable motors to a common pressure source for simultaneous operation.

Figure 3 is a modified form of the reversing valve means shown in Figure 2.

Figure 4 is a view showing the method of coupling more than two motors to a common pressure line for simultaneous operation.

Figure 5 is a modified form of circuit for preventing overrun of the motors.

Figure 6 is a detailed view showing the relationship of the tapered portions of the automatically adjustable resistance compensating valve with respect to the motor delivery ports therein.

It is a well-known hydraulic principle that the pressure of a fluid in a closed vessel is equal in all directions. If two hydraulic motors, such as 10 and 11 as seen in Figure 1, are connected directly to a pump 12 they will run at equal rates, only and if, the work resistances of the motors are equal, because the channels by which the two motors are connected to the pump may be considered as a single closed vessel in which the pressure must and will be equal in all directions.

Since unequal pressure therefore cannot exist for any appreciable time in the same volume of fluid, it is apparent that if the rotational resistance of motor 10 rises above that of motor 11, the former will slow down, while the speed of the latter will be increased. This is due to the fact that the pressure in the supply line to motor 10 did not rise in proportion to the load and thereby maintain the same rate of fluid consumption. Furthermore, it could not rise sufficiently for this purpose when the existing pressure was sufficient to force the excess fluid not utilized by motor 10 through the motor 11 causing the same to speed up. In other words if the proportionate rates were maintained, it would be necessary to have two different pressures coexisting in one closed vessel which is impossible. It thus follows that if the work resistances of the two motors are not maintained constant and equal, the motors will not operate at the same velocity but rather one will accelerate and the other decelerate.

45 This invention contemplates mechanism for connecting a plurality of motors to a common pressure source whereby each will operate at the same rate or at proportionately different rates irrespective of the rise or fall of the work resistances of the respective motors. For the purposes of explanation, it is assumed that the displacement of each motor is the same for a given velocity. It is therefore apparent that actual movement is determined by volumetric fluid con-

consumption by each motor. If equal volumetric quantities can be supplied to each motor having similar rates of displacement it is apparent that they will both operate at the same velocity. 5 But work resistances vary, and therefore the respective quantities supplied to the motors will normally vary. As previously explained, the work resistance differential in an open system affects the quantity supplied and therefore causes a variation in rate. It thus becomes apparent that if means are provided for maintaining the quantity constant irrespective of variation in the work pressures that each motor will move at the same velocity. 10 15 Since the pressure in each of the branch lines 13 and 14 leading to the respective motors depends upon the respective work resistances, it will be seen that a rise in the work resistance of the motor 10 would cause a corresponding pressure rise in the supply line 13 if there was no other avenue of escape for the fluid in the system. The same thing would be true with respect to the motor 11 and the channel 14; but if the two motors are directly connected to a common supply a 20 25 rise in the work resistance of motor 10 causes more fluid to escape through the lower resistance represented by the motor 11 instead of effecting a proportionate rise in the pressure line 13. 30 It should therefore be apparent that if a resistance was inserted in the line 14 equal in effect to the rise in work resistance of the motor 10 over the work resistance of the motor 11, that the total resistance of line 14 and motor 11 would 35 then be equal in effect to the work resistance of the motor 10, and thus the pressure required by the two lines would then be equal and the motors would operate at the same velocity. This resistance must have the proper value to maintain, at 40 the inlet side thereof, a pressure corresponding to the pressure in channel 13, and at the outlet side thereof, a pressure corresponding to that required to overcome the work resistance of the motor 11. 45 In an open circuit such a resistance would effect this result because any resistance inserted in a flow channel causes a drop of pressure across the resistance in relation to the quantity flowing through it, and thus the pressure at the inlet side 50 will be higher than the pressure at the outlet. It is only necessary to adjust the resistance to obtain sufficient pressure differential so that the pressure on the inlet side will equal the increased pressure of the other branch line; and at the 55 outlet side a pressure corresponding to that required to overcome the resistance of the respective motor actuated thereby.

Furthermore, from a practical standpoint this inserted resistance must be automatic in operation so that the slightest variation in the resistance of one motor will be compensated by a corresponding increase in the resistance of the other branch line in order to maintain equal operation of the parts. In the present instance this 60 resistance is in the form of a valve which may be termed a resistance compensating valve comprising a casing 15 in which is reciprocably mounted a plunger 16. This plunger, as shown in the drawing, may be provided with tapered ends 17 and 17'. The intersection of the cylindrical portion of the valve with the tapered portion is represented respectively by lines 18 and 18'.

Spaced ports 19 and 20 are formed in the valve casing to which are connected respectively the channels 13 and 14 leading to motors 10 and 11.

The relationship of the lines 13 and 14 to the ports 19 and 20 may be such that when the plunger 16 is in a central position relative to its casing, the line 18 will pass through the center of the port 19, and the line 18' will pass through the center of the port 20 as more particularly shown in Figure 6 whereby each port will be in a half-closed position thereby offering equal amounts of resistance to flow therethrough. This is the more practical form as it creates an initial 10 resistance and prevents a slight delay in the operation of the valve such as would occur were the valve flat at the ends and shortened to provide a full opening of the port. Pressure is supplied to opposite ends of the valve casing through ports 21 and 22 to which the branch lines 23 and 24 are respectively connected. These branch lines have arranged therein resistances 30 and 29 respectively and are connected to the common pressure channel 25 supplied by pump 12 which may be a constant or a variable displacement type and which may draw fluid from a reservoir 26 through the inlet line 27. If so desired an emergency relief valve 28 may be inserted in the line 25 to protect the parts against excessive high pressure. 15 20 25

If the resistances 29 and 30 are equal, as in the case where an equal supply to two motors is desired, and if the work resistances of the motors are equal, and if the valve plunger 16 is in a central position, it is obvious that there will be an 30 equal drop in pressure in each line 23 and 24 thereby equalizing the flow or volume between the lines, and also equalizing the pressures in chambers 31 and 32. A rise in work resistance in motor 10 will momentarily retard the input flow thereto 35 causing a piling up of fluid in chamber 31 and a momentary rise in the pressure existing therein. Since this pressure will be higher than the pressure in the opposite chamber 32, it will be seen that the valve plunger 16 will move slightly downward as viewed in Figure 1. The effect of this downward movement is to further close the port 20 and simultaneously add to the opening of port 19. As previously explained this increases the 40 resistance of port 20 and decreases the resistance 45 of port 19. The increase in resistance at port 20 causes an increase in the pressure differential across this port, the pressure on the supply side thereof rising still higher above the pressure at the motor side of port 20. This pressure rise 50 which will occur in chamber 32 will continue until it equals the pressure in chamber 31 which results in re-establishing an equal pressure drop across resistances 29 and 30 in channels 24 and 23 thereby maintaining the equal division of 55 quantity between these channels.

The plunger 16 may therefore be considered as having a valve portion on one end and a piston portion at the other end for effecting insertion of the resistance in the line 14; similarly, if the resistance of motor 11 should rise above the work resistance of motor 10 the pressure in chamber 32 will increase over the pressure of chamber 31 causing movement of the plunger 16 upward and the insertion of resistance in the line 13. The 60 plunger therefore acts automatically to raise the resistance of the particular motor channel having the lower resistance, thereby preventing the cross effect of one motor on the other, that is of constituting a low resistance preventing a sufficient 65 rise in pressure of the other to meet a rise in work resistance. It will thus be seen that when the work resistances of the two motors are equal and operating at the same rate, the valve 16 will be 70 in a central position while a rise in work re- 75

sistance of either will effect a corresponding shifting of the valve to increase the resistance 30 in the opposing line and thereby make possible the sustaining of a higher pressure.

5 If it is desired to operate the motors at relatively different speeds such as the operation of the motor 11 at twice the velocity of the motor 10, the resistances such as 29 and 30 must be inversely proportional to the speeds desired. If the 10 resistance 29 is greater than the resistance 30 as shown in Figure 1 while the pressure drop across them is equal, it will be seen that more fluid will flow through the resistance 30, and since quantity determines speed, the motor 11 will travel faster 15 than the motor 10. These resistances may be in the form of small tubing provided with couplings at opposite ends for selective coupling in either line and may be of various lengths for providing a selection of relative speeds. Since the valve 16 20 will shift back and forth until the pressures in chambers 31 and 32 are equal, it will be seen that the pressures at ports 21 and 22 will finally equalize and therefore the drop in pressure across the resistance 29 will be equal to the drop in 25 pressure across the resistance 30. The quantity, however, passing through each resistance will vary in inverse proportion to the value of the resistance itself, and this is true because the pressure in each branch line, that is, at the inlet port 30 of the resistances, is equal. Since, for a limited range the pressure may be considered to be equal to the product of the quantity and the resistance, if the resistances vary, the quantities must vary inversely in order that their product will be the 35 same. Since the valve 16 will operate in the same manner as before, it will be seen that the resistances 29 and 30 divide the flow into proportionate parts and that the valve 16 maintains these proportions irrespective of variations in 40 work resistances.

Attention is invited to the fact that these proportions are maintained or in other words are substantially unaffected by changes in viscosity and temperature of the working fluid. It is 5 recognized that the value of a resistance will vary as the viscosity which, for a given fluid is an inverse function of the temperature. Thus the higher the temperature of the oil, the greater will be the flow for a given pressure drop. 0 Thus it will be seen that in the present construction the resistances being equal or in definite proportions, that the same proportional effect will be produced on each branch line by changes in temperature and viscosity and therefore will 5 not have any unbalancing effect.

A more adjustable form of flow dividing device is illustrated in Figure 2 and comprises a casing 33 in which is reciprocably mounted a valve plunger member 34 which is operatively connected to an adjusting screw 35 threaded in the end of the casing. This plunger has a reduced intermediate portion 36 which is tapered at the ends 37 and 38 to form a throttle for the outlet ports 39 and 40. Pressure is supplied from the pump 12 through the port 42 and in accordance with the longitudinal position of the plunger, the flow will be proportionately divided between the ports 40 and 39. As shown in this figure, the motors may constitute the piston and cylinder type such as 10' and 11' in which case the usual procedure would be to provide reversing valves 43 and 44 whereby the operated parts may be given a reciprocating motion. The reversing valve plungers 43' and 44' may be joined into a single plunger 45' as

shown in Figure 3 for effecting simultaneous reversal of motor movement.

The flow in either branch line may be further subdivided as shown in Figure 4 to effect operation of more than two motors. Only one subdivision is shown but it will be apparent that the subdivision may be carried out with one line or with both lines to effect simultaneous operation of as many motors as desired. If three motors 10'', 55, and 56 are to be operated at 10 the same rate, the resistance 45 would probably be given the value of twice the resistance 46 whereby one-third of the flow will pass through port 47 of valve 48 and two-thirds of the flow 15 pass through port 49. This latter quantity can be divided equally between the ports 50 and 51 of the valve 52 or proportionate resistances such as 53 and 54 may be utilized to effect a rate differential between the last two motors. The operation will be substantially the same, compensation for differences in the work resistance of 20 motors 55 and 56 being automatically provided by the plunger 57 while the desired relationship between the flow through outlet port 49 and outlet port 47 will be maintained by the plunger 25 58 in valve casing 48. Separate reversing valves similar to those illustrated in Figure 2 may be inserted at 59 in the circuit illustrated in Figure 4 to effect reciprocation of the motors.

In the arrangements so far described it will 30 be apparent that if flow was cut off from either motor, that there is nothing to prevent the motor and actuated parts from overrunning due to their momentum, and therefore in such cases where it is desired to prevent overrun, an arrangement such as shown in Figure 5 may be utilized. In this case the resistance compensating valve is inserted in the exhaust or return lines rather than in the forward pressure line. For instance, branch lines 62 and 63 connected 40 respectively with lines 23 and 24 serve to conduct the pressures thereof to opposite chambers 32' and 31' of the valve for action on opposite ends of the plunger 16'. This plunger has annular grooves 64 and 65 having beveled sides 45/ 66 and 67 which act to partially close the ports 20' and 19' to which are connected the return channels 60 and 61 respectively of motors 11 and 10. Ports 21' and 22' of the valve are connected to a common return line 68 which may in 50 some cases be connected to the pump intake line 21. The operation of the valve is the same as just described to maintain proportionate division of flow to the motors with the additional effect that any further restriction of port 19' 55 or 20' will have a retarding effect to prevent overrunning of the motor and parts due to any momentum it may have.

It will thus be seen that mechanism has been provided for connecting two or more hydraulically actuated motors in parallel with a common source of pressure for uniform operation thereby, at the same velocity or at respectively different velocities. It will be noted that the division of flow is effected in such a manner 65 that the divisions are unaffected by changes in viscosity or temperature of the fluid or by variations in the work resistances of the respective motors.

That which is claimed is:

1. An hydraulic power system combining a volumetrically constant pressure supply, a plurality of motors, branch channels connecting the motors in parallel to the pressure supply, and means operable by resistance pressures in the 75

4. input side of the motors to maintain constant the quantities delivered by the branch channels to the respective motors independent of relative variations in the work resistances of the respective motors.
5. 2. An hydraulic system for operating a plurality of motors in parallel comprising a volumetrically constant source of pressure, parallel branch lines connecting the source of pressure to the respective motors, means to divide all the flow from said source proportionately between the branch lines in accordance with the relative rates desired in said motors, and means operable by pressure variation in the motor input line due to variable motor resistance to maintain the volumetric flow divisions and thereby the relative rates of said motors constant.
6. 3. In an hydraulic system the combination of a volumetrically constant source of pressure, a plurality of motors each adapted to overcome variable work resistances, branch lines connecting the respective motors in parallel to said source of pressure, and means to maintain a predetermined relation between the velocities of the respective motors comprising a first resistance means for each branch to determine the normal proportional distribution of flow between the branches of the respective motors; additional variable resistance means and means coupling said variable resistance means for reactance by the input pressures of the motors of the respective branches, whereby said second variable resistance means are automatically actuatable to compensate for variation in the work resistance of one motor relative to the other whereby the total resistance to fluid flow in each branch will be maintained constant and equal thereby maintaining the velocity ratio of the motors constant.
7. 4. An hydraulic system combining a volumetrically constant source of pressure, a pair of motors to be actuated thereby, parallel branch lines connecting the pressure to the input side of the motors, a variable resistance in one branch line connected to cause a pressure drop between said source and said input side of the motor, and means responsive to pressure variations in the other line caused by increase in the work resistance thereof to increase the resistance in said one branch line to maintain the velocity ratio of said motors constant.
8. 5. An hydraulic system combining a volumetrically constant source of pressure, a pair of hydraulic motors, branch supply channels connecting the source of pressure to the intake side of the motors, a variable resistance in each branch line between the source of pressure and the motors and fluid operable means responsive to a pressure increase in either line relative to the other to increase correspondingly the resistance in the opposite line to maintain the ratio between the motor velocities constant.
9. 6. An hydraulic circuit a volumetrically constant source of pressure, a plurality of operating motors, individual channels connecting the respective motors in parallel to said source of pressure, and valve means in each channel responsive to relative variations between the pressures in the respective lines on the intake side of said motors to maintain the quantity ratio between the flow to each channel constant and thereby insure a constant velocity ratio between the motors.
10. 7. In an hydraulic circuit a source of pressure, a plurality of branch lines, a flow dividing valve for coupling the source of pressure to said lines and proportioning the flow therebetween, an hydraulic motor connected to each branch line and resistance compensating means associated with the respective branch lines between said valves and the respective motors for maintaining the flow division constant whereby the quantity supplied to each motor will be maintained at a predetermined constant thereby preventing relative variation between the rates of movement of the respective motors.
11. 8. In an hydraulic circuit the combination of a pump capable of positively delivering a constant volumetric supply to a main line, a plurality of hydraulic motors to be operated at predetermined unequal rates by said pump including individual branch lines extending from the main line to the motors, means to divide the total flow from the pump into said branch lines in unequal proportions in accordance with said rates, said means including hydraulic resistances inversely proportional to the quantity of flow necessary to effect the desired rates and valve means connected to receive the discharge from said resistances and responsive to work variations in the motors to maintain said unequal proportions constant and thereby operation of the motors at the predetermined unequal rates.
12. 9. In an hydraulic circuit a source of pressure, a plurality of branch lines, a flow dividing valve for coupling the source of pressure to said branch lines and proportioning the flow therebetween, an hydraulic motor connected to each branch line, means in each branch line to reverse the direction of the respective motors, and resistance compensating means arranged in each branch line for maintaining the flow division constant whereby the quantity supplied to each motor will be maintained at a predetermined constant, thereby preventing relative variation between the rates of movement of the respective motors in either direction of operation.
13. 10. An hydraulic transmission for effecting joint operation of a plurality of hydraulically actuated devices at predetermined proportionate rates including means for establishing a constant volumetric flow, means to divide said flow in accordance with said rates among said devices for effecting actuation thereof at said proportionate rates including valve means for varying said quantities to change the performance ratio of said devices during actuation thereof, and automatic fluid operable means to maintain said quantities as determined by said valve means constant during operation of said devices.
14. 11. An hydraulic system for effecting joint operation of a pair of hydraulically actuated devices, each including an hydraulic motor, a pump, a flow dividing valve coupled to the pump, a resistance compensating valve comprising a valve casing, inlet ports at opposite ends of the casing, means connecting said ports to the flow dividing valve, a pair of spaced outlet ports, a reciprocable plunger mounted in the casing, individual channels connecting the outlet ports to the respective motors whereby a relative pressure increase in either motor will be communicated to its respective port and thereby the end of the plunger adjacent thereto causing shifting of the same, and means on the opposite end of the plunger for constricting the outlet port to the other motor.
15. 12. An hydraulic system for effecting joint operation of a pair of motors including a common volumetrically constant source of pressure, parallel branch lines extending from the source

of pressure to the individual motors, means to divide the flow between the channels, a variable resistance in each channel between the flow dividing means and the respective motors, and 5 hydraulically actuated means for varying the resistance in one line in accordance with the increase in work resistance in the other line.

13. An hydraulic system for effecting parallel operation of a plurality of hydraulic motors including a common source of pressure, parallel branch lines extending to the individual motors, means to divide the main flow into two divisions, 10 means to connect one division to one of said parallel lines, means to subdivide the other division between the remaining parallel lines, and valve 15 means responsive to pressure changes in said lines to maintain all of said divisions constant irrespective of work resistance variation of the respective motors.

14. An hydraulic system for maintaining pre-determined proportionate rates of operation of a pair of hydraulic motors each of said motors having an inlet port and an exhaust port, comprising a pump, channel means extending from the 20 pump to said motor inlet ports whereby all the output of said pump will be delivered to said motors, said channels including a main conduit for receiving the full output of said pump, branch 25 conduits extending from the main conduit to the respective motors, means in each branch conduit

for determining the volumetric proportion of the main flow to pass therethrough and thereby the rate of operation of the respective motors, valve means in each branch conduit between the flow determining means and the motor for maintaining an equal pressure drop in the branch conduits, 10 each of said valve means being responsive to a rise in pressure in the other branch to effect a rise in pressure in its own branch and means to connect the exhaust ports of said motors to reservoir whereby the back pressure on each motor will be the same.

15. An hydraulic power system combining a volumetrically constant pressure supply, a plurality of motors, branch channels connecting the 15 motors in parallel to the pressure supply, a first resistance means in each channel complementally variable to determine volumetrically the proportions of the main flow passing through each branch and thereby the ratio of the rate of operation of said motors, additional serially arranged resistance means in each channel for maintaining the volumetric ratio of the flows including fluid operable means for complementally changing the values of the last named resistances inversely 20 25 in accordance with changes in working pressures developed by said motors in their respective supply lines.

HANS ERNST.
